(57) CLAIM

The ornamental design for a bookshelf as shown and described.

DESCRIPTION

FIG. 1 is a front, top, and left perspective view of a bookshelf showing the new design;

FIG. 2 is a front, top, and left perspective view thereof with a door in a second position;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof;

FIG. 8 is a right elevation view thereof;

FIG. 9 is a front, top, and left perspective view of a second embodiment of a bookshelf showing the new design.

FIG. 10 is a front, top, and left perspective view thereof with a door in a second position.

FIG. 11 is a front elevation view thereof.

FIG. 12 is a rear elevation view thereof;

FIG. 13 is a top plan view thereof;

FIG. 14 is a bottom plan view thereof;

FIG. 15 is a left elevation view thereof; and,

FIG. 16 is a right elevation view thereof.

The dashed lines in the drawings illustrate portions of the bookshelf that form no part of the claimed design.

1 Claim, 12 Drawing Sheets
